UNITED STATES PATENT OFFICE.

JOHN R. NOCK AND KIRIAKOS PRODIS, OF BROOKLYN, NEW YORK.

AUTOMATIC STARTING AND STOPPING DEVICE FOR PHONOGRAHS.

Application filed December 14, 1927. Serial No. 240,037.

This invention relates to phonograph stopping and starting devices and in particular to one which is automatic in its operation.

A particular object of the invention is to provide an automatic starting and stopping device for use in connection with phonographs which, after automatically stopping the operation of the turntable, will automatically restart the same when the tone arm is moved to a predetermined position.

A still further object of the invention is to provide a device of this character which may be secured to any phonograph in use without altering the arrangement of any of the parts and one which will effectively operate in conjunction with records having different widths of grooves cut therein, it being well understood that various manufacturers of records use coarser needles to reproduce and the length of selection of various records is different, consequently the number of grooves per space on records varies and as the result, in some records, the needle of the phonograph tone arm moves a greater distance to play a particular feature than it would on a phonograph record of a different make, consequently, some means must be incorporated in an automatic device of the character referred to which will compensate for the various grooved portions of different records.

A still further object of the invention is to provide a simplified mechanism having few parts which will not get out of order and which may be secured to any phonograph with a minimum of time and labor.

To enable others skilled in the art to fully comprehend the underlying features of our invention that they may embody the same in the various modifications in structure and relation contemplated, a drawing depicting a preferred form has been annexed as a part of this disclosure and in such drawing, similar reference characters denote corresponding parts throughout all the views, of which,

Figure 1 is a top plan view of the phonograph starting and stopping mechanism constructed in accordance with our invention.

Figure 2 is a view in side elevation of the mechanism illustrated in Figure 1.

Figure 3 is an enlarged view in sectional elevation of a portion of the mechanism showing the end of the tone arm lever in contact with an intermediate slide pin arrangement, and

Figure 4 is a fragmentary section showing a portion of the brake and the brake pad in the position it occupies when in contact with the inner periphery of a turn table flange.

Referring to the drawings in detail, 5 indicates a tone arm of the usual type which is pivotally supported in the tone arm base 6 secured in any suitable manner to the phonograph casing 7. This tone arm carries the usual reproducing unit and needle, not shown, 65 it being sufficient to note that the tone arm 5 is revolvably mounted in the tone arm base 6 and this turning movement permits the sound box and its accompanying needle to be placed in the inner or outer reaches of the 70 groove that is cut in the record, the record being indicated in the drawing by the numeral 8 and being mounted in the usual manner on the turn table 9 which is provided with a depending edge flange 10. This turn table 75 is usually made of metal and is operated in the well known manner to rapidly revolve the disc so that the reproduction of the selection on the record is carried out.

We are quite well aware of the fact that 80 stops have been provided which are set to a predetermined position and at the end of the selection a cut in the record, will automatically operate to stop the turn table. However, to our knowledge, we have gone a 85 step further and have provided an automatic device which will, when the needle is placed at the beginning of the record, automatically release the braking mechanism and allow the turn table to continue its operation and in 90 carrying out our mechanism, we provide a clamp 11 which, through the medium of the bolts 12, is secured about the tone arm 5, its movement therearound being prevented by suitable set screws 13 which are threaded 95 through a tone arm lever portion 14, there being cast integral with this portion, a tone arm lever 15. This tone arm lever, as illustrated in Figure 3, may be substantially U-shaped and may be arranged to carry in its 100 outer end, the adjusting screw 16, this screw being provided at one end with a head 17 and at its other end with a knurled finger knob 18, the screw in its intermediate portion carrying the locking nut 19 through the medium 105 of which it may be secured at any position of its threaded adjustment in the tone arm lever 15. The purpose of this adjusting screw is to compensate for the various makes of records and it is quite evident from a further descrip- 110

tion of the mechanism that the longitudinal adjustment of the screw through the tone arm lever 15 will cause the operation of the other mechanism at a predetermined time, or after 5 the tone arm lever has swung through a predetermined length of arc during the playing of the record.

It is quite evident that the tone arm lever will, of course, swing with the tone arm 10 whose swinging motion is caused by arcuate travel of the needle relatively to the record 8 during the playing of a selection and in order to transfer the motion of the tone arm lever 15, I have provided in the path of the 15 head 17 of the adjusting screw, an intermediate slide pin 20, this pin being provided on its ends with the flanges 21, one of which is adapted to be engaged by the head 17 to slide the pin 20 through the standard 22 which is 20 suitably secured to the phonograph case 7. The flange 21 at the opposite end of the pin 20 is adapted to engage the enlarged end 23 of a dog 24, the dog itself being pivoted as at 25 to a bed plate 26 which is secured to the 25 phonograph case 7 at a point beneath the turn table and adjacent the flange thereof. The end of the dog 24 is hooked as at 27 to engage a suitable notch 28 formed in the periphery of a brake member 29, this brake 30 member is also pivoted as at 30 to the bed plate 26. The dog 24 is connected through the medium of a tension spring 31 with the upstanding arm 32 which is cast integral with the bed plate 26 so that the hook 27 is 35 normally urged into connection with the brake member 29. This brake member being pivoted, can revolve to a position where its extended portion 34, carrying the braking pad 33, will come into contact with the inner 40 surface of the depending flange 10 of the turn table 9. In order that the pad 33 will be normally urged toward the flange of the turn table, we have provided as indicated by the numeral 35 a coil spring which connects 45 a suitable lip 37 formed on the brake member 29 with a suitable lip 36 on the bed plate 26.

The brake member 29 is further provided with a link arm 38 to the outer end of which is connected through the medium of a pin 50 and slot connection, the link 39 which is pivoted as at 40 to the tone arm lever 15, the slot of the link is indicated by the numeral 40 and therein the pin 41, carried on the end of the link arm 38 has free movement or 55 rather, the end of the link has free movement about the pin and the mechanism as illustrated in Figure 1 might be considered to be in the position that it will assume during the playing of a record, the travel of the needle 60 swinging the tone arm 5 in the position indicated by the arrow in Figure 1 until the needle is in the final groove of the record at which time, the head 17 of the adjusting screw 16 will contact with the slide pin 20 65 causing it in turn to strike the portion 23 of

the dog 24 thereby revolving the dog on its pivot point against the action of the spring 31 until the hooked end 27 disengages the brake member 29 at which time the spring 35 will revolve it about its pivot point 30 and 70 throw the pad or brake member 33 against the inner surface of the flange 10 of the turn table, thus causing the latter to stop. At this time, the record may be replaced and upon 75 swinging the needle back to the starting groove, the tone arm will be revolved in a counter clock-wise direction with the result that the link 39 will be drawn up to the position shown in Figure 1 and through the medium of the pin and slot connection with the 80 brake member 29 will revolve the brake member in an anti-clock-wise direction until the notch 28 in the periphery thereof is engaged by the hook 27 of the dog 24 at which time, of course, the pad 33 will have been removed 85 from its contact with the flange of the turn table and the latter will be allowed to revolve.

It is quite evident, therefore, that we have provided a combination starting and stopping mechanism for phonographs which is entirely automatic in its operation and one which may be attached to any phonograph in use without materially altering the parts thereof. 90

It is also quite evident that we have provided an automatic stopping and starting mechanism for phonographs which may be adjusted to compensate for the various widths of selections cut on the faces of records. 100

It is evident also, that we have provided an automatic starting and stopping mechanism for phonographs which can be applied with a minimum of time and labor and one 105 which will conserve the energy of the spring by immediately stopping the turn table when the selection has been completely played and also will start it at the proper time or when the needle of the sound box has been placed substantially adjacent the outer groove in the record. 110

While we have illustrated and described our invention with some degree of particularity, we realize that in practice various alterations therein may be made. We therefore reserve the right and privilege of changing the form of the details of construction or otherwise altering the arrangement of the correlated parts without departing from the 115 spirit of the invention or the scope of the appended claims. 120

Having thus described our invention what we claim as new and desire to secure by United States Letters Patent is:— 125

1. The combination with a phonograph comprising a movable reproducing unit carrying arm and a record carrying turn table; of a stop member, a spring for normally urging the stop member against the turn table an 130

extension on the arm, a latch for holding said stop member, a standard, and a pin freely slideable therein and operable by a movement of said extension for releasing said latch to 5 permit operation of said stop member.

2. The combination with a phonograph comprising a movable reproducing unit carrying arm and a record carrying turn table; of a stop member, a spring for normally urging the stop member against the turn table, an extension on the arm, a link on the arm movable to a position to permit operation of said stop member, said link constituting an automatic starting device, a latch for holding 10 said stop member in inoperative position and means operable by a movement of said extension for releasing said latch to permit operation of said stop member.

3. The combination with a phonograph comprising a movable reproducing unit carrying arm and a record carrying turn table; of a stop member, a spring for normally urging the stop member against the turn table, an extension on the arm, a link on the 15 arm movable to a position to permit operation of said stop member, a latch for holding said stop member in inoperative position, means operable by a movement of said extension for releasing said latch to permit operation of said stop member and said link being further operable to reset said stop member after the same has functioned.

4. The combination with a phonograph comprising a movable reproducing unit carrying arm and a record carrying turn table; of a pivoted stop member, means for normally urging it to operative position against the turn table, a dog for holding the stop at inoperative position, an extension on 20 the arm, an intermediate freely sliding member in the path of the extension for releasing said dog to permit operation of said stop, and an adjusting screw carried by said extension for making contact with said sliding member.

45 5. The combination with a phonograph comprising a movable reproducing unit carrying arm and a record carrying turn table; of a pivoted stop member, means for

normally urging it to operative position against the turn table, a dog for holding the 50 stop at inoperative position and an extension on the arm, an intermediate slide member in the path of the extension for releasing said dog to permit operation of said stop, a link 55 connecting the extension and the stop member and having a pin and slot attachment to the latter whereby free operation of the stop member is permitted when the dog is released and said link operating to move the stop to inoperative position when the extension is 60 moved in a direction away from said slide member.

6. The combination with a phonograph comprising a movable reproducing unit carrying arm and a record carrying turn 65 table; of an extension attached to the arm, a pivoted turn table engaging stop, a spring for normally urging the stop toward said turn table, a dog for releasably holding the stop out of turn table engagement, a freely movable slide in the path of said extension for operating the dog and an adjusting screw in 70 said extension for operating said slide when the extension has moved a predetermined distance.

7. The combination with a phonograph comprising a movable reproducing unit carrying arm and a record carrying turn table; of an extension adjustably secured to the arm, a pivoted turn table engaging stop, a 75 spring for normally urging the stop toward the turn table, a dog for releasably holding the stop out of turn table engagement, a slide in the path of said extension for operating the dog, an adjusting screw in said extension 80 for operating said slide when the extension has moved a predetermined distance in one direction and a link for moving the stop out of engagement with the turn table and into position to be held by the dog when the extension 85 has moved a predetermined distance in the opposite direction.

In testimony whereof we affix our signatures.
